(57) **CLAIM**

The ornamental design for an ultrasonic horn for insertion of z-direction composite rods, as shown.

DESCRIPTION

FIG. 1 is a perspective view of the ornamental design of an ultrasonic horn for insertion of z-direction composite rods showing our new design. The broken lines show the environment and do not form a part of the design of the claimed invention.

FIG. 2 is an enlarged perspective view of the ultrasonic horn for insertion of z-direction composite rods;

FIG. 3 is a top view of the ultrasonic horn for insertion of z-direction composite rods;

FIG. 4 is a front view of the ultrasonic horn for insertion of z-direction composite rods; and,

FIG. 5 is a side view of the ultrasonic horn for insertion of z-direction composite rods.
